E. RIBACK.

WINDOW SCREEN.

APPLICATION FILED OCT. 22, 1909.

963,393.

Patented July 5, 1910.

UNITED STATES PATENT OFFICE.

ELIAS RIBACK, OF CHICAGO, ILLINOIS, ASSIGNOR OF THIRTY-FIVE ONE-HUNDREDTHS
TO MAX SIEGEL, OF CHICAGO, ILLINOIS.

WINDOW-SCREEN.

963,393.

Specification of Letters Patent.

Patented July 5, 1910.

Application filed October 22, 1909. Serial No. 524,012.

To all whom it may concern:

Be it known that I, ELIAS RIBACK, a citizen of the United States, and a resident of the city of Chicago, in the county of Cook and State of Illinois, have invented certain new and useful Improvements in Window-Screens, of which the following, when taken in connection with the drawing accompanying and forming a part hereof, is a full and 10 complete description sufficient to enable those skilled in the art to which it pertains to understand, make, and use the same.

This invention relates to window screens used to prevent flies or other insects passing 15 through open windows.

The object of this invention is to obtain a window screen which will not be in place before a window opening when the window thereof is closed and which will be automatically put in place before the window opening as the window is opened.

A further object of the invention is to obtain a window screen of the kind described which may be easily detached so that the 25 window may be raised without automatically placing the screen before the opening thereof; and also a device which may easily be entirely removed from the window and readily replaced thereon, when desired.

30 A further object is to obtain a device of the kind named which will be certain in operation and require no care on the part of the operator and which when the window is closed will be protected from wind, rain and snow.

In the drawing referred to Figure 1 is a front elevation, from outside a building, of a window provided with a device embodying this invention, said window and device being closed. Fig. 2 is a vertical sectional view of said window and device, on line 2—2 of Fig. 1, viewed in the direction indicated by the arrow. Fig. 3 is a vertical sectional view of a window having a device embodying this invention attached thereto, said window and device being partially open. Fig. 4 is an end elevation, on an enlarged scale, of a device embodying this invention. Fig. 5 is a plan view of a 45 portion of one of the members of the screen of the device. Fig. 6 is a plan view of a portion of a base forming an element of the device. Fig. 7 is a vertical section of a latch and lifting pin forming an element of the

device. Fig. 8 is an end elevation of an element forming the cover of the device.

A reference letter applied to indicate a given part is used to indicate such part throughout the several figures of the drawing wherever the same appears.

A is a window frame, *a* the sill thereof.

B is a window sash and *b* the horizontal lower bar of the sill.

C, C, are pins provided with lugs C', C', arranged to form a base, which is secured to 65 bar *b* of the window sash B. Pin C is hollow and provided with groove C'.

D is a latch which is provided with the end *d* and with pin or rod *d'*.

E is a spring on pin or rod *d'*. Latch D 70 is yieldingly held in the position illustrated in Fig. 7 by spring E, and may be forced back against the resiliency of said spring in groove C'. End *d* of latch D, is arranged to engage with rod or bar F of one 75 of the members of the screen G to attach one edge of said member to the window sash.

The screen G comprises the members *g*, *g'*, *g''*, *g'''* which are pivotally attached together at their adjacent edges by hinges H, 80 H, H. The member *g* is pivotally attached to base I by hinge H'. Hinges H, respectively, are constructed so that the pivots *h*, *h*, thereof stand out from the planes in which the members *g*, *g'*, *g''*, and *g'''* lie; and 85 said hinges are attached to the members which are joined together thereby so that said pivots are parallel to but set back from the edge of at least one of said members.

What I term the "overhang" which is obtained by this set back of the hinge is lettered J in Figs. 3 and 4, and this overhang 90 protects the joints of the several members of the screen, when the screen is open, so that flies or insects can not pass through the device; and also said overhang provides for the proper folding of the members of the screen when the window is closed. The base

I is removably fastened in place on window sill *a* by screws K, in slots *i*. Screws 100 K are shown as consisting of the well known eyelet headed screws, so that when said eyelet heads are in the same planes as the slots *i*, they will pass freely therethrough, and when in planes at right angles to the planes 105 of the slots will not pass therethrough.

L, L, are covers which are, respectively hinged to bases M, M, by pivots *m*. Bases

M are secured to the sides of frame A, so that the covers L, L, when down will rest on the member g''' of screen G and cover it and when up will be in a plane parallel with the sides of frame A, (see Fig. 3). When the covers L, L, are up and the members of the screen are in inclined planes, during the opening and closing of the window, or when the window is partially opened 10 (as in Fig. 3), said covers close the openings at the ends of the screens. When the covers L, L, are down they overlap each other, and N, N, are grooves which fit together, one over the other, at such time. As the window 15 sash B is raised pins C, C, raise covers L, L, (that is turn them on pivots m from a horizontal into a vertical position), and as the sash is lowered said pins permit said covers to resume a horizontal position.

20 To permit adjustment of the members g , g' , g'' , and g''' (making them longer or shorter) to make the screens fit windows varying in width, each of said members is made of two pieces of screen p , p' , overlapping above midway of the window, (see Fig. 5). The members g , g' , g'' , and g''' as made by me have what is called the selvage edge of wire screen along the sides thereof and the ends, being what are termed 25 raw edges, are bound by sheet metal binding P.

The operation of the device is;—When rod F is engaged with end d and sash B is raised a given distance the covers L, L, are 30 turned from a horizontal to a vertical position; and members g'' , g'' , of the screen are raised into the position thereof illustrated in Fig. 3. Further raising of said sash will first bring said members g'' , g'' , into vertical planes, and continued raising of said sash will ultimately raise all of the members g , g' , g'' and g''' into vertical planes. When the sash is closed the members g , g' , g'' , and g''' will assume the 35 folded position illustrated in Figs. 1 and 2 and covers L, L, will assume a horizontal position over them.

Having thus described my invention what I claim as new and desire to secure by Letters Patent is;—

1. The combination of a plurality of wire screens pivotally attached together, means to pivotally attach one edge of an end one of said screens to a window sill, and means to pivotally attach one edge of the other end 55 one of said screens to a window sash, with a plurality of pivotally mounted covers respectively arranged to rest on said screens when said screens are folded together, and means to automatically turn said covers on their pivots to raise them off the screens, when the window sash is raised.

2. The combination of a plurality of wire screens each of said screens comprising a plurality of members adjustably attached 65 together, said screens pivotally attached together, means to pivotally attach one edge of an end one of said screens to a window sill, means to pivotally attach one edge of the other end one of said screens to a window sash, with a plurality of pivotally mounted covers, respectively arranged to rest on said screens when said screens are folded together, and to overlap each other, and means to automatically turn said covers 70 on their pivots to raise them off the screens when the window sash is raised.

3. The combination of a plurality of wire screens pivotally attached together, removable means to pivotally attach one edge of 80 an end one of said screens to a window sill, and removable means to pivotally attach one edge of the other end one of said screens to a window sash, with a plurality of pivotally mounted covers respectively arranged 85 to rest on said screens when said screens are folded together, and means to automatically turn said covers on their pivots to raise them off the screens when the window sash is raised.

ELIAS RIBACK.

In the presence of—

CHARLES TURNER BROWN,
CORA A. ADAMS.
